UNITED STATES PATENT OFFICE.

ALBERT V. WALDO, OF DEGRAFF, OHIO.

INTERNAL-COMBUSTION ENGINE.

1,078,392.

Specification of Letters Patent. Patented Nov. 11, 1913.

Application filed June 13, 1912. Serial No. 703,542.

To all whom it may concern:

Be it known that I, ALBERT V. WALDO, a citizen of the United States, resident of De-
graft, in the county of Logan and State of
Ohio, have made a certain new and useful
invention in Internal-Combustion Engines;
and I declare the following to be a full,
clear, and exact description of the same,
such as will enable others skilled in the art
10 to which it appertains to make and use the
invention, reference being had to the accom-
panying drawings, and to letters or figures
of reference marked thereon, which
form a part of this specification.

15 Figure 1 is a section on the line 1—1, Fig.
3. Fig. 2 is a section on the line 2—2, Fig.
1. Fig. 3 is a section on the line 3—3, Fig. 1.

The invention has relation to internal
combustion engines, and it consists in the
20 novel construction and combinations of
parts, as hereinafter set forth.

In the accompanying drawings illustrating
the invention, the numeral 1, designates
one of the four cylinders of the engine; 2,
25 the piston working therein; 3, 3' lateral pis-
ton valve chambers, 4, 4' piston valves work-
ing in said chambers; 5, a water jacket lin-
ing for the cylinder and chambers, and 6, 6'
30 valve ports from the chambers to the cylin-
der.

As usual with four-cycle engines, to which
my invention relates, the piston has a stroke
in one direction for charging, a stroke in the
opposite direction to compress the charge, a
35 stroke under the impulse of the exploded
charge for driving and a stroke back again
to exhaust the charge, the pistons of the
four cylinders, (only one of which is shown)
being arranged to act successively upon the
40 crank shaft to drive it.

The piston valves are operated in any suit-
able manner preferably by means of a train
of gears 7, 7', cranks 8, 8', and connecting
rods 9, 9' from the cranked shaft 10, of the
45 end gear of the train; the crank shaft 11,
having a connecting rod 12, with the pis-
ton, and carrying the other end gear of the
train of gears. In the operation of the en-
gine the train of gears will move the pis-
50 ton valves to expose the inlet port 6 upon
the charging stroke only of the piston, and
to expose the exhaust port 6', upon the ex-
haust stroke only of the piston, these ports
being closed upon the other strokes.

55 Each piston valve is provided with pack-
ing rings 13, and in order that the material

of these rings may not be liable to expand
through the valve ports 6, 6', it is preferred
to provide these ports with intermediate
oblique cross bars 14, 14'. 60

In the operation of the engine, the explo-
sive mixture is admitted to the chamber 3
at 16, being drawn thereinto by movement
of the piston valve, starting from substan-
tial contact with the top of said chamber and
when the valve port 6 is exposed, this mix-
ture is drawn into the cylinder, the piston
of which is upon its charging stroke. Af-
ter the charge has been drawn into the cyl-
inder, the valve port is closed by the piston
valve, and the piston is operated reversely
70 to compress the charge, which is exploded
by the igniting or sparking device 17 at the
proper time. The piston is now driven
back by the impulse of the charge, and the
75 fourth stroke of the piston, completing the
cycle, acts to expel the exhausted gases
through the port 6', which is opened by
movement of the piston valve 4'. At the
end of the exhaust stroke of the working 80
piston the piston valve 4', now upon its up-
stroke, will have closed port 6', and, contin-
uing to the top of the exhaust chamber 3'
into substantial contact therewith, will force
the exhausted gas out through the exhaust 85
port, communicating with the chamber
through the end wall thereof.

The piston valve chambers or cylinders 3,
3', are arranged with their axes at an angle
to the axis of the working cylinder, to over-
hang the same, so that the castings may be
90 made more compact and the ports made as
short as possible, the ports being measured
in length at the center by the thickness of
the cylinder wall; while providing for am-
95 ple water-jacketing and for a location of
the ports intermediately of the length of
the valve chambers.

My invention is designed to increase the
efficiency of the engine, to render the opera-
100 tion of the valves more reliable, and repairs
more easily made.

Having thus described my invention, what
I claim as new and desire to secure by Let-
ters Patent is:— 105

1. In an internal combustion engine, a
cylinder, a working piston therein, inlet and
exhaust chambers having intermediately of
their length lateral ports communicating
110 with said cylinder, inlet and exhaust ports
in the end walls of said chambers, piston
valves working in said chambers, means for

- operating one of said valves to draw the explosive mixture into the inlet chamber, to uncover the lateral port thereof upon the charging stroke of the working piston and 5 to close said port upon the other strokes thereof, and means for operating the other of said valves to uncover the lateral port of the exhaust chamber upon the exhaust stroke of the working piston, to close said port 10 during the other strokes of said piston and to clear the exhaust chamber of the burnt gases, said valves having respectively at one end substantial contact with the entire end walls of said chambers at the beginning of 15 the intake and end of the exhaust stroke.
2. In an internal combustion engine, a working cylinder, a piston therein, cylindrical inlet and exhaust chambers axially inclined with relation to and having a water jacket space between the same and said working cylinder, said chambers having intermediately of their length short lateral ports measured at the center in length by the thickness of the cylinder wall and communicating with the upper portion of said 20 25
- cylinder, inlet and exhaust ports in the end walls of said chambers, piston valves in said chambers, means for operating one of said valves to draw the explosive mixture into the inlet chamber, to uncover the lateral port thereof upon the charging stroke of the working piston and to close said port upon the other strokes thereof, and means for operating the other of said valves to uncover the lateral port of the exhaust chamber upon the exhaust stroke of the working piston, to close said port upon the other strokes of said piston and to clear the exhaust chamber of the burnt gases, said valves having respectively at one end substantial contact with the entire end walls of said chambers at the beginning of the intake and end of the exhaust strokes. 30 35 40

In testimony whereof I affix my signature, in presence of two witnesses.

ALBERT V. WALDO.
